INVENTOR.
 Theodore M. Cox
 BY John C. Watson
 ATTORNEY.

UNITED STATES PATENT OFFICE.

THEODORE M. COX, OF ALBANY, NEW YORK, ASSIGNOR TO COX BRASS MANUFACTURING COMPANY, OF ALBANY, NEW YORK.

AUTOMOBILE-BUFFER.

1,381,170.

Specification of Letters Patent. Patented June 14, 1921.

Application filed June 11, 1920, Serial No. 388,321. Renewed March 8, 1921. Serial No. 449,501.

To all whom it may concern:

Be it known that I, THEODORE M. Cox, a citizen of the United States of America, residing at Albany, in the county of Albany 5 and State of New York, have invented certain new and useful Improvements in Automobile-Buffers, of which the following is a specification.

My invention relates to spring buffers such 10 as are attached to the front or rear of automobiles.

The object of my present invention being 15 to improve and cheapen the construction of the impact receiving member of the buffer and the means for attaching the buffer to an automobile, together with such other elements and combinations as are hereinafter more particularly set forth and subsequently claimed.

20 The manner in which I attain my objects is illustrated in the accompanying drawing in which:

Figure I. is a plan view of my improved buffer.

25 Fig. II. is a rear elevation of Fig. I.

Fig. III. is a front elevation of the buffer.

Fig. IV. is a side elevation of my improved buffer on a large scale and illustrates the adjustable attaching means.

30 Fig. V. is an enlarged detail along the line 5-5 on Fig. I.

The same reference letters refer to the same parts throughout the several views.

The buffer and attaching means here illustrated are an improvement on the automobile buffer previously invented by, and for which William G. Cox was granted U. S. Letters Patent on April 6, 1920, said patent bearing the number 1,385,877.

40 Referring to the drawings, A, is a resilient impact receiving member, made from a single piece of material, looped as shown, so that the ends come together at or near the center of the front bar of the loop. The

45 free ends of the looped members are then joined together by means of the reinforcing strip B, which is preferably attached thereto by means of suitable bolts and nuts, N. N.

A clip member E, adapted to closely fit 50 against one side and both edges of the looped member A, covers the point where the ends of the looped member meet. A suitable bolt L, passing through the reinforcing strip B, between the ends of the looped member A,

and through the clip member E, co-acts with 55 a nut O, and joins the whole securely together in a neat manner. A lock-washer P, is provided to prevent accidental loosening of the nut O, and similar lock-washers are preferably provided under all nuts used with 60 the device.

Curved resilient supporting members C, 65 C, are adjustably attached to the resilient impact receiving member A. Slotted openings c, c, provide means whereby the supporting members may be adjusted to fit various widths of frames. Suitable bolts and nuts M, M, are used to attach the impact receiving member to the supporting members. Adjustably attached to the ends 70 of the supporting members C, C, are the attachment plates D, D. The attachment plate D, is provided with a slotted opening d, and the end of the supporting member is preferably provided with two holes. A bolt and 75 nut H (with a suitable lock-washer) are used to fasten the attachment plate to the end of the supporting member. The side of the attachment plate D, adapted to contact with the automobile frame K, is recessed so 80 as to receive the head of the bolt H, as indicated in Figs. I and IV.

A hook bolt F, extending through a supporting member C, and one end of the attachment plate D, is adapted to engage with 85 one flange of the side bar K, of an automobile frame. A similar hook-bolt G, extending through the opposite end of the attachment plate, is adapted to engage with the opposite flange of the side bar K. See Figs. 90 I, II and IV.

In the previous patent before referred to, the impact receiving member was a continuous loop, the front bar arched to add strength.

95 This member was made by looping a piece of high grade carbon steel and welding the ends together.

My improved buffer has a loop of substantially the same shape, but instead of welding so as to form a continuous loop, the joint is made by bolting a strap to the abutting ends, and covering the point with a clip.

The additional strap makes an effective 105 reinforcement and is less expensive than the cost of making a suitable weld in the class of material used.

Referring to Fig. IV, which illustrates my attachment means, it will be clearly seen that the bolt F, will act as a fulcrum about which the buffer may be oscillated to bring the impact receiving member to the desired level.

What I claim as new and desire to secure by Letters Patent is:

1. In an automobile buffer, an impact receiving member comprising a single piece of flat spring material formed into an elongated loop and a reinforcing strap joining the free ends of said loop; means for mounting said impact receiving member on an automobile so that both bars of the looped member thereof lie in a substantially horizontal plane across the end and in front of said automobile and parallel to the axles thereof.
2. In an automobile buffer, an impact receiving member comprising a single piece of flat spring material formed into an elongated loop having rounded ends slightly curved in the plane of the loop sides and a reinforcing strap joining the free ends of said loop; means for mounting said impact receiving member on an automobile so that both bars of the looped member thereof lie in a substantially horizontal plane across the end and in front of said automobile and parallel to the axles thereof.
3. In an automobile buffer, an impact receiving member comprising a single piece of flat spring material formed into an elongated loop having rounded ends slightly curved in the plane of the loop sides, and a reinforcing strap joining the free ends of said loop; rearwardly extending supporting members adjustably connected to said impact receiving member; and means for removably attaching said supporting members to the side bars of an automobile frame.
4. In an automobile buffer, an impact receiving member comprising a single piece of flat spring material formed into an elongated loop having rounded ends slightly curved in the plane of the loop sides, and a reinforcing strap joining the free ends of said loop; curved rearwardly extending resilient supporting members adjustably attached to said impact receiving member; and means for removably and adjustably attach-

ing said supporting members to the side bars of an automobile frame.

5. In an automobile buffer, an impact receiving member comprising a single piece of flat spring material formed into an elongated loop having rounded ends slightly curved in the plane of the loop sides, and a reinforcing strap joining the free ends of said loop; curved rearwardly extending resilient supporting members adjustably attached to said impact receiving member, attachment plates adjustably attached to the ends of said supporting members; a hook bolt extending through said supporting member and one end of said attachment plate, the hook end thereof adapted to engage with one of the flanges on a channeled side bar of an automobile frame; a hook-bolt extending through the other end of said attachment plate the hook end thereof adapted to engage with the other flange on said side bar; and nuts co-acting with said hook-bolts to clamp said attachment plates and said supporting members securely to the side bar of an automobile frame.

6. In attaching devices for adjustably attaching automobile buffers to the side frame members of an automobile, an attachment plate through said supporting member and one near each end thereof, and a slotted hole transversely of said plate and between said bolt holes, said attachment plate recessed about said slotted opening to receive the head of a bolt adjustable in said slot; a bolt, and a nut co-acting therewith to bind said attachment plate to the end of a supporting member of a buffer; a hook-bolt extending through said supporting member and one end of said attachment plate; the hook end thereof adapted to engage one of the flanges on a channeled side bar of said frame; a hook-bolt extending through the other end of said attachment plate the hook end thereof adapted to engage with the other flange of said side bar; and nuts co-acting with said hook-bolts to clamp said attachment plates and said supporting members securely to the side bar of an automobile frame.

In testimony whereof I have affixed my signature.

THEODORE M. COX.
